UNITED STATES PATENT OFFICE.

IRA RALPH BUCHANAN, OF YELM, WASHINGTON.

VALVE-LIFTING TOOL.

1,307,772.

Specification of Letters Patent. Patented June 24, 1919.

Application filed October 22, 1918. Serial No. 259,232.

To all whom it may concern:

Be it known that I, IRA R. BUCHANAN, a citizen of the United States, residing at Yelm, in the county of Thurston and State of Washington, have invented certain new and useful Improvements in Valve-Lifting Tools, of which the following is a specification, reference being had to the accompanying drawings.

10 This invention relates to an improved valve lifting tool, and has for its primary object to provide a simple and easily applied device for the purpose of compressing the valve spring and allowing the valve to move downwardly to its open position so that it may be easily cleaned or removed for the purpose of regrounding the valve and its seat.

15 It is another important object of the invention to provide a device for the above purpose which is so constructed that both hands of the mechanic are free, whereby the work may be greatly expedited.

20 It is also one of the detail objects of the invention to provide a valve spring lifting lever, and an adjustable fulcrum for said lever, whereby it may be operatively applied to motor valves having stems of various lengths.

25 With the above and other objects in view, the invention consists in the improved construction, combination and relative arrangement of the several parts as will be herein-after more fully described, subsequently 30 claimed and illustrated in the accompanying drawing in which similar reference characters designate corresponding parts throughout the several views; and wherein—

35 Figure 1 is a side elevation showing one embodiment of my improved tool as applied in practical use;

40 Fig. 2 is a section taken on the line 2—2 of Fig. 1;

45 Fig. 3 is a plan view of the foot plate of the lifter; and

50 Fig. 4 is a detail perspective view of the adjustable fulcrum plate for the lever.

55 Referring in detail to the drawing, 5 designates a vertically disposed body bar having a laterally off-set portion 6 formed with a longitudinally extending slot 7 therein. To one end of this bar, a horizontally disposed handle 8 is integrally connected. The other end of the body bar is curved, as shown at 9, and is formed with a gradually widen-

ing, horizontally disposed foot plate 10. This foot plate at its extremity is recessed, 60 and formed with a countersink 11, and at the edge of said recess, which is adapted to receive the lower valve spring washer. Thus, lateral shifting movement of the washer plate and its frictional contact with the valve stem or rod will be prevented. 65 A lever 13 extends through the slot 7 of the body bar 5 and is fulcrumed upon a pin 15 connecting the arms of a bifurcated plate 14, between which said lever extends. A bolt 16 has its headed end engaged in the slot 7 and extends through an opening in the opposite end of the plate 14 and through a coinciding opening in the washer 17 which is interposed between said plate and the side 70 of the body bar 5. A clamping nut 18 of any suitable type is threaded upon the other end of said bolt to securely clamp the plate 14 in its adjusted position upon the body bar. 75

By adjusting said plate, it will be readily understood that the fulcrum 15 for the lever may be disposed at the requisite distance from the foot plate 12 so that the end of the lever 13 can be properly applied to the valve spring. A ring or link 19 is permanently engaged in an eye 20 on the end of the handle 8. The distance between the fulcrum 15 and the bolt 16 is such that in any adjustment of the plate 14 upon the body bar, the lever 13 is normally disposed at such an angle relative to the handle 8 that the end thereof, corresponding to the end of the handle provided with the link 19, is disposed an appreciable distance below said link. 85 90

In the application of the device, it will be understood that the foot plate 10 is operatively engaged with the lower valve spring washer, as above explained, and the lever 13 properly adjusted so that its shorter end will extend above the valve stem. The operator now forces the opposite end of said lever toward the handle 8 so that the valve is forced downwardly and the spring compressed. The ring or link 19 is then engaged over the end of the lever 13 so that both hands of the mechanic will be free for the purpose of grinding the valve face or its seat. The device may be very easily and quickly removed to permit the return of the valve to its normal position by simply disengaging the link from the end of the lever 13. 100 105 110

From the foregoing description, taken in

connection with the accompanying drawing, the construction, manner of operation and several advantages of the device will be clearly and fully understood. The several parts of the invention are all of very simple and durable construction and can be easily and quickly assembled or disassembled. Owing to the provision of the adjustable fulcrum for the valve lifting lever, the device can be readily applied to different types of motor vehicle engines. In view of the simplicity of the construction of my improved valve lifter, it will further be appreciated that the device can be manufactured at relatively small cost.

While I have herein shown and described the preferred construction and relative arrangement of the several parts, it is to be understood that the device is susceptible of considerable modification and I, accordingly, reserve the privilege of adopting all such legitimate changes as may be fairly embodied within the spirit and scope of the invention as claimed.

I claim:—

1. A valve lifting tool including a body bar having an angular intermediate portion and a foot plate extending in one direction from said intermediate portion recessed to receive the valve spring washer, a handle extending in a relatively opposite direction from the intermediate portion of the body bar, said medial portion of the body bar having a slot therein, a valve spring compressing lever extending through said slot, a fulcrum for said lever mounted upon the body bar.
2. A valve lifting tool including a body

bar having an angular intermediate portion and a foot plate extending in one direction from said intermediate portion recessed to receive the valve spring washer, a handle extending in a relatively opposite direction from the intermediate portion of the body bar, said medial portion of the body bar having a slot therein, a valve spring compressing lever extending through said slot, a fulcrum for said lever mounted upon the body bar, and said fulcrum being provided with means whereby said fulcrum may be adjusted to position the same relative to the foot plate.

3. A valve lifting tool including a body bar having an angular intermediate portion and a foot plate extending in one direction from said intermediate portion recessed to receive the valve spring washer, a handle extending in a relatively opposite direction from the intermediate portion of the body bar, said medial portion of the body bar having a slot therein, a valve spring compressing lever extending through said slot, a bifurcated plate arranged on one side of the body bar, a fulcrum pin for the lever connecting the spaced arms in said plate, and a clamping bolt for the plate adjustable in the slot of said body bar, whereby the fulcrum of the lever may be positioned relative to the foot plate.

In testimony whereof I hereunto affix my signature in the presence of two witnesses.

IRA RALPH BUCHANAN.
